UNITED STATES PATENT OFFICE.

IRA G. BERRY, OF ROCK FALLS, ILLINOIS, ASSIGNOR TO THE KEYSTONE MANUFACTURING COMPANY, OF SAME PLACE.

CORN-SHELLER.

SPECIFICATION forming part of Letters Patent No. 637,698, dated November 21, 1899.

Application filed February 21, 1898. Serial No. 671,207. (No model.)

To all whom it may concern:

Be it known that I, IRA G. BERRY, a citizen of the United States, residing at Rock Falls, in the county of Whiteside, in the State of Illinois, have invented certain new and useful Improvements in Corn-Shellers, of which the following is a description, reference being had to the accompanying drawings, forming part of this specification.

10 My improvements relate to corn-shellers of a familiar style, examples of which may be found illustrated in Letters Patent of the United States No. 522,669, granted July 10, 1894, to George W. Packer, and in a number of 15 prior patents referred to therein. Reference may be had to these patents for a more detailed description of the general construction and operation of the machine than will be found necessary here to an explanation of my 20 present invention.

The novelty of my invention will be hereinafter set forth, and particularly pointed out in the claims.

In the accompanying drawings, Figure 1 is 25 a vertical longitudinal section of part of a corn-sheller, showing one set of shelling devices and illustrating my present improvements. Fig. 2 is an enlarged detail perspective view of the two-part hinged concave section, and Fig. 3 an enlarged cross-sectional detail of the bottom of one of the feed troughs or chutes and the chain traveling therein.

The same letters of reference are used to indicate identical parts in all the views.

30 A represents the main frame and casing of the machine, having at its under side a discharge-opening B for the shelled corn and at its forward side the main feed trough or hopper C, which is provided at its bottom with a series of longitudinal troughs or feed-chutes C', one for each set of shelling devices, as usual. Traveling in the bottom of each of the feed-troughs C' is an endless feed-chain D, which at its upper rear end passes 35 around a sprocket-wheel upon a rotary shaft E and at its lower rear end around a sprocket-wheel upon another shaft. (Not shown.) Each of the sprocket-wheels upon the shaft E is located between two outwardly-flaring wheels 40 or disks F, provided with radial ribs and fast upon the shaft E, each pair of wheels forming

a rotating continuation of the sides of one of the feed-troughs C', by means of which the ears carried upward and rearward along said troughs by the chains D are guided from the 55 troughs and delivered to the shelling devices.

G is the rotating picker-wheel of one set of shelling devices, and H the picker-shaft. Located beneath the shaft H is the member commonly termed the "concave" or "concave section" of the shelling device. It forms the bottom of the throat or passage through which the ear of corn is forced, while the shaft H forms the top of such passage and the picker-wheel G the left-hand wall thereof, the right-hand wall thereof being formed by a fixed wall or partition of the frame of the machine, the view in Fig. 1 being taken just beyond or to the left of such fixed partition. It is to this hinged bottom of the shelling-passage 70 that the first feature of my invention relates. As shown in Fig. 2, this element is in the present instance formed of two members I and I'. The member I is hinged at its upper forward end to the side wall of the shelling 75 chamber or passage at a, while pivoted to its lower rear end at b is the upper end of a curved rod J, which extends downward and forward through the inclined wall K of the casing. The extreme forward end of the rod 80 J passes through a fixed cross-piece L, and in rear of said cross-piece is surrounded by a coiled spring M, which is confined between the cross-piece L at its forward end and an adjusting-nut N upon the rod J at its rear end, 85 as shown and described in detail in the patent before mentioned. The pressure of the spring M against the nut N presses the rod J upward and rearward and yieldingly holds the rear end of the member I in the normal 90 position to which it may be adjusted, but permits it to be forced downward by the passage of the ears of corn between it and the picker-shaft H, as hereinafter described. The rear end of the member I is shaped to form a guide-rib e, concentric to the pivot a of the member, which rib fits in a notch in a lug f, projecting from the fixed side wall of the shelling-passage and serves to guide the rear end of the member in its vertical movements and 100 prevent lateral play thereof, as explained in the patent before mentioned. Hinged to the

member I at the upper side of its rear end at c is the upper member I' of the concave device. The forward end of this member I' has pivoted to its under side at d the upper end 5 of a rod O, which passes downward through the member I and has a pin passed through its extreme lower end beneath the member I. A coiled spring P, surrounding the rod O between the members I and I', presses the forward end of the member I' upward and yieldingly holds it in its normal upper position. The upper surface of the member I' is serrated diagonally, as usual, to engage the grains of corn upon the ear and facilitate the shelling. 10 The forward end of the member I' is guided vertically on a rib g, formed upon the member I.

In the Packer patent, No. 522,669, heretofore referred to, and in the machines built 20 under and in accordance with said patent, the concave consisted of a single member hinged at its upper forward end at c and yieldingly held in its normal upper position by the spring-pressed rod J and adjusted by means 25 of the nut N upon said rod, the upper surface of such single member being serrated and occupying substantially the position of the member I' in the present instance. The objection to this construction was that when 30 one part of the member was moved by the forcing of an ear of corn between it and the picker-shaft above it the entire member was necessarily swung downward upon its pivot a, the result of which was that if a large ear 35 of corn immediately followed a small ear in passing through the shelling devices the front end of the large ear as it was forced between the upper surface of the concave and under surface of the picker-shaft at the forward end 40 of the entrance to the passage between those two members would swing the concave so far downward as to entirely release the smaller ear of corn in front of it before the shelling of such smaller ear was completed, and thus 45 it would happen that partially-unshelled ears of corn would pass through the machine and be delivered therefrom with the cobs. The construction of the concave in two members I and I', hinged together at one end and pressed 50 apart by a spring at the other, as above described, completely overcomes the objection to the former construction above explained and insures the complete and perfect shelling 55 of all the ears of corn, regardless of their relative size and the order in which they pass through the shelling devices. As the front end of a large ear of corn enters the passage between the picker-shaft H and the forward end of the concave section I' it will simply 60 press down the forward end of the section I' against the resistance of the spring P and will not press down the rear end of the section I against the resistance of the spring M until it reaches the space between the rear 65 end of such section and the picker-shaft H, so that if the ear in front of it be a smaller one it will not be released by the rear end

of the section I and the picker-shaft until its grains have been completely removed from the cob.

The second feature of my invention relates to a construction and arrangement for insuring the delivery of the ears of corn by the feeding devices to the shelling devices in more regular order than heretofore. The 75 endless feed-chains D have heretofore usually traveled over and entirely above the bottoms of the feed-troughs C', with the result that the entire chain was exposed to the ears of corn in such troughs. The result of this was 80 that the ears of corn would be carried upward to the shelling devices not only by contact of the chain-teeth D' with their ends, as intended, but also by the links of the chain between such teeth. Owing to this fact two ears of 85 corn would be frequently carried up in the same trough side by side or the ears advanced in other irregular order instead of in a single line, and inasmuch as they can enter the shelling devices properly only in single line 90 crowding and choking of some of the ears sometimes occurred at the entrance to the shelling devices. I have overcome this difficulty by locating the feed-chain proper entirely below the bottom of the feed-trough 95 and providing the latter with a narrow longitudinal slot just wide enough to permit the passage of the teeth D', projecting from the chain, as shown in Figs. 1 and 3. Under this arrangement there is nothing in the feed-trough to engage the ears of corn excepting the upper ends of the teeth or projections D' upon the chain, and these projections are of such size that they cannot engage more than one ear of corn at a time. The result is that 105 no matter how nearly filled the main hopper or trough C may be with ears of corn each chain D will carry upward only a single row of ears in its subtrough C', and thus deliver 110 the ears to the separate passages of the shell- 115 ing devices in single rows.

Having thus fully described my invention, I claim—

1. In a corn-sheller, the herein-described concave section, composed of the lower member I pivotally supported at its forward end and yieldingly supported at its rear end, the upper member I' hinged to the lower member I near its rear end, and a spring P interposed between the members I and I', for the 120 purpose set forth.

2. In a corn-sheller, the herein-described concave section, composed of the lower member I pivotally supported at its forward end, the upper member I' hinged to the lower member I near its rear end, the rod O connected at its upper end to the forward end of the member I' and guided at its lower end by the member I, and the coiled spring P surrounding the rod O between the members I and I', for the purpose described.

3. In a corn-sheller, the concave section composed of the pivoted member I, the member I' hinged to the member I, and the spring

P interposed between the two members, in combination with the rod J coöperating with the member I, and the spring M and adjusting-nut N upon said rod, substantially as described.

4. In a corn-sheller, a concave comprising a member yieldingly supported at its rear end, a second member carried by said first member, and means for yieldingly supporting the forward end of said second member, substantially as described.

5. In a corn-sheller, the combination of a

lower concave member, means for yieldingly supporting its rear end, an upper member pivoted to the lower member at its rear, a spring interposed between said members for yieldingly supporting the forward end of the upper member, and guiding means for the forward end of said upper member, substantially as described.

IRA G. BERRY.
